UNITED STATES PATENT OFFICE.

CHARLES H. ANDERSON, OF CINCINNATI, OHIO.

WINDOW CONSTRUCTION.

1,244,825,

Specification of Letters Patent.

Patented Oct. 30, 1917.

Application filed June 28, 1916. Serial No. 106,409.

To all whom it may concern:

Be it known that I, CHARLES H. ANDERSON, a citizen of the United States, and a resident of Cincinnati, in the county of Hamilton and State of Ohio, have invented certain new and useful Improvements in Window Constructions; and I do hereby declare the following to be a full, clear, and exact description of the invention, such as will enable others skilled in the art to which it appertains to make and use the same.

This invention relates to windows and more particularly to car windows,—one object of the invention being to provide simple and efficient sash guide devices and mountings so that the sashes may have a close but easy sliding and substantially air-tight fit relatively to a T-bar window post, such as employed in car constructions.

With this and other objects in view, the invention consists in certain novel features of construction and combinations of parts as hereinafter set forth and pointed out in the claims.

In the accompanying drawings, Figure 1 is a horizontal sectional view through a T-bar window post and parts of two sashes, and Fig. 2 is a perspective view of the guide or slide sheets.

1 represents a window post in the form of a T-bar, the web portion and also the flanges of which are made somewhat tapering in cross section, so that the sides of the web portion and the under faces of the flanges

present inclined beveled surfaces. Posts of this construction do not of themselves form desirable runways for sashes and in order to provide a proper fit, I employ slides or guides 2, 2. Each slide or guide 2 com-

prises a sheet of metal having a part 3 bent or folded upon itself and securely riveted, as at 4 to the web of the window post so as to form a smooth and flat surface against which, a weather strip 5 on a sash 6 may slide,—such sashes being shown in Fig. 1 at respective sides of the window post and two guide sheets being employed on the post.

From the outer portion of the part 3 of each guide sheet, the metal of the same extends laterally behind one of the window post flanges, as at 7, and is provided with an outwardly projecting rib 8 to engage the inner face of said flange of the post and thus cause the lateral member 7 of the guide sheet to be disposed in a plane at right angles to the transverse axis of the post and parallel

with the outer face of the adjacent sash rail, so that the latter may have a flat outer sliding bearing relatively to the window post. Each guide sheet or bracket 2 is formed at its free edge with a loop 9 which embraces the free edge portion of the window post flange and the free edge of this loop portion engages the outer face of said post flange. Thus it will be seen that the rib 8 performs an additional function, when co-operating with the loop 9, to grip or clamp the guide sheet or bracket to the flange of the T-post.

The weather strips 5 of flexible material are located on the free edges of the vertical rails of the sashes, and when the latter are in place in the window frame, these strips 5 will be bent to U-shape, the bent edge being engaged by a rib or flange 10 on the rail 70 of the sash. Each weather strip 5 is held by a metal retaining strip 11 which lies against the face of said weather strip and is secured to the rail by means of screws 12. One edge of the retaining strip 11 extends 75 approximately to the bent edge of the weather strip, so that said bent edge will be located between one edge of the strip 11 and the flange or rib 12 of said rail. The retaining strip 11 projects out from between the 80 members of the bent weather strip 5 and is formed with a shoulder 13 projecting toward the plane of the free member of the weather strip, and with an extension 14 which engages the inner face of the sash rail. 90

It will be observed that the weather strips 5 on adjacent sashes form cushions between said sashes and the slide or guide brackets 2 and thus take up play of the sashes and form weather-tight joints.

Having fully described my invention what I claim as new and desire to secure by Letters-Patent, is:

1. The combination with a window post having a web and a flange, of a guide bracket comprising a single sheet having a part secured to the web portion of the post and having a lateral portion to receive one face of a sash rail, said lateral portion engaging the flange of the window post. 100

2. The combination with a window post having a web and a flange, the latter having a beveled inner face, of a guide sheet or bracket secured to the web of the post and having a lateral portion, said lateral portion 110 having a rib engaging the inner beveled face of the post flange and causing said lateral

portion to be disposed at approximately right angles to the transverse axis of the web portion of the post.

3. The combination with a window post 5 comprising a web and a flange, of a guide sheet or bracket comprising a part secured to the web of the post, a lateral portion having a rib engaging the inner face of the flange of the post, and a loop gripping said 10 post flange.

4. The combination with a T-bar window post having beveled web and flange portions, of guide sheets or brackets each comprising a member folded upon itself and secured to 15 the web of the post, a lateral member having a rib engaging the flange of the post, and a loop gripping said flange.

Copies of this patent may be obtained for five cents each, by addressing the "Commissioner of Patents, Washington, D. C."

5. The combination with a window post and a sash, of a guide bracket for the sash, secured to the post, a bent flexible weather strip disposed on an edge of the sash and having a free portion engaging said guide bracket, and a metal strip disposed between the members of the bent weather strip and secured to one member thereof and to the 25 sash, said metal strip having a part engaging the inner face of the sash.

In testimony whereof, I have signed this specification in the presence of two subscribing witnesses.

CHARLES H. ANDERSON.
